LOUIS B. GOLDBERG, NATHAN GOLDBERG, WILLIAM GOLDBERG, AND JACOB M. GOLDBERG, OF DENVER, COLORADO.

CAMP STOVE.

Application filed September 17, 1923. Serial No. 663,090.

To all whom it may concern:

Be it known that we, LOUIS B. GOLDBERG, NATHAN GOLDBERG, WILLIAM GOLDBERG, and JACOB M. GOLDBERG, citizens of the United States, residing at Denver, county of Denver, and State of Colorado, have invented certain new and useful Improvements in Camp Stoves; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in gasoline stoves and has particular reference to that type of stove generally referred to as "camp stoves."

The advent of the automobile has ushered in an era of roving which has developed to such an extent that a considerable proportion of our population is constantly on the move during the summer months. In order to be come independent of the hotels, it is customary for people traveling with automobiles to carry camping equipment, including cooking utensils. To obviate the necessity of building wood fires and to enable cooking to be done when wood is unavailable, it has been proposed that compact gasoline stoves be carried, and many different stoves have been invented for this purpose.

It is the object of this invention to improve the construction of this type of stove so as to overcome certain objections and thereby to produce a stove that shall be more satisfactory than similar stoves now on the market.

In order to better and more clearly describe our invention, we shall have reference to the accompanying drawing in which the preferred form thereof is shown, and in which:

Fig. 1 is a top plan view of our improved stove in open operative position, parts thereof being broken away to more clearly disclose the construction;

Fig. 2 is a longitudinal, vertical section taken on line 2—2, Fig. 1;

Fig. 3 is a transverse vertical section taken on line 3—3, Fig. 1;

Fig. 4 is a side elevation of the plunger portion of the valve;

Fig. 5 is a section taken on line 5—5, Fig. 55 3; and

Fig. 6 is a section taken on line 6—6, Fig. 3.

The same reference characters will be employed to designate the same parts throughout the several views.

Numerical 1 represents a rectangular box which has a cover 2 hinged to the upper edge of one side thereof and which forms a carrying case and may also be considered as the 65 stove frame. The burners or the stove proper consists of a central tubular member 3 whose ends are closed by cup-shaped plugs 4 autogenously welded thereto. At a point 5, substantially midway between the ends of 70 member 3, is a vapor-receiving chamber 6, one end of which is welded to the opening in tube 3 and the other end of which extends parallel to the same. A plate 7 closes the end of member 6. This plate has an opening 75 for the reception of the fuel supply pipe 8 which extends from the fuel reservoir 9 and is provided with a control valve 10. Plate 7 also has a cuplike portion 11 which receives and holds a small amount of gasoline, by the 80 combustion of which the pipe 8 is heated sufficiently to convert the gasoline therein into vapor which then passes into the vapor chamber 6 and into the interior of tubular member 3. The gases which leave the end of 85 pipe 8 with considerable force, cause air to enter through the open end 12 and to be added thereto in sufficient quantity to form a combustible mixture. At each end of member 3 there is located a burner consisting of 90 a funnel-shaped, pressed steel member 13 whose narrow end is welded or otherwise secured to the sides of opening 14 in pipe 3. The wide end of the funnel has its edges 15 bent upwardly so as to form a seat for the 95 burner 16. The tubular member 3 is supported by an M-shaped bracket having vertical sides 17 terminating in feet 18 which are perforated for the reception of screws 19 which have thread connection with lugs 20 100 on grate 21. The grate has feet 22 that rest upon the upper surface of the burner 16 and in combination with the screws 19, holds the parts in place. The tubular member rests in the bottom of the notch 23. A strap 24 has its center perforated and lies between the upper surface of the tubular member 3 and the bottom of the funnel-shaped mem-

ber 13. The ends of the strap 24 have lugs 25 which can be bent about the strap 17 in the manner shown most clearly in Fig. 5. The action of the strap 24 is to hold the tubular member against any rotary movement.

As it is desirable to have at least two burners and as it is often unnecessary to use more than one, it is necessary to provide a valve mechanism by means of which the 10 burners that are not needed can be closed off and when in use can be regulated. Our valve means comprise a plunger 26, shown in elevation in Fig. 4. This plunger has a central stem 27, to the upper end of which 15 is secured a part having tapering sides 28, to the lower edge of which are attached downwardly projecting lugs 29 which serve as guides. The tubular member 3 and the supporting bracket 17 are perforated for the 20 reception of the stem 27 which has a diametrical opening 30 near its lower end. The plunger 26 can move to open, dotted line position, Fig. 3, or to closed full line position and may occupy any intermediate position. The means for controlling the position of the plunger consists of a rod 31 whose end 32 projects through a hole in one 25 of the vertical legs of the bracket 17. Rod 31 also passes through the opening 30 and has its other end cooperatively connected to the end of the crank arm 33 of rod 34. Rod 34 is journaled in suitable openings in the 30 ends of supporting member 35. A spring 36 surrounds the rod 34 and serves to spread the ends of the bracket 35 apart so as to produce sufficient friction to hold the rod from rotating of its own accord. It will 35 also be noted that the spring 36 fits the rod 34 snugly at one end so as to cause considerable friction when there is relative rotation between the spring and rod. A tubular member 37 has a head 38 and a longitudinal slot 39. A pin 40 secured to the rod 34 projects through slot 39 and prevents 40 relative rotation while permitting a limited longitudinal movement. The object of the telescopic arrangement between rod 34 and the tubular shank 37 is to permit the valve handle to be pulled out into the position 45 shown in Fig. 1 or pushed back into the casting so as to prevent it from becoming bent or broken.

The tubular member 3 is of a special construction which is of very light weight and of great strength, being formed of two substantially identical semi-cylindrical sections which I have designated as "a" and "b." These sections have cooperating flanges *c* which are autogenously welded. The ends 50 are closed by cup-shaped members 4, also welded to the ends of the tubular member. The vapor receiving chamber 6 is formed of two supplementary parts welded together at *d* and is welded to the tubular member 3. The construction just described produces an

element having all of the advantages of a heavy cast-iron piece and only a small part of the latter's weight, which is an item of considerable importance in a portable stove.

Another advantage of the light-weight 70 construction of the tubular member 3 is that it heats up very readily and thereby makes it easier to start the stove, as well as improving the operation after it has started.

Attention is called to the fact that when 75 the rod 34 is rotated, for the purpose of operating the valve, the lever 31, owing to its crooked shape and to the fact that it passes through a hole in the end of the stem and through another hole in the bracket, will 80 be caused to rotate. The bent end 32 will engage the foot 18, when the valve is fully open, and act as a stop.

The stove described above operates in the same manner as ordinary stoves of this type. 85 The gasoline is contained in an air-tight cylindrical reservoir 9, into which air is also forced. The pressure of the air tends to force the gasoline out through the pipe 8 which passes over one of the burners and projects into the vapor-receiving chamber. To start the stove, a small quantity of gasoline is placed in the cup 11 and ignited. This heats the gasoline in pipe 8 and converts it 90 into a gas which mixes with air in the receiving chamber 6 and flows from thence to the burner 13 where it burns and keeps pipe 8 hot. If more than one burner is needed, the knob 38 is turned and this opens the valve, permitting gas to flow out and by adjusting valve 10 the volume of gas generated 95 can be regulated.

Having now described our invention, what we claim as new is:

1. In a gas gurner having an opening for the entrance of gas; means for controlling the effective size of said opening, said means comprising a valve member having a conical head whose largest diameter is greater than the diameter of said opening and whose 105 smaller diameter is less than the diameter of the opening, downwardly projecting spaced members extending from the smaller end of said conical head; a central valve stem secured to said head; and means for moving said valve member, said means comprising a 110 lever.

2. In a gas burner for stoves; a bracket; a tubular member supported by said bracket, said tubular member having its ends closed 120 and provided with openings near each end; a funnel-shaped member secured to the tubular member, said funnel-shaped member having an opening in register with the opening in the tubular member; a conical valve member reciprocably mounted in said opening, said valve member having a central stem adapted to extend through an opening in said tubular member; a lever pivoted at one 125 end to said bracket; a member rotatably 130

connected to the bracket; a crank arm at the end of said rotatable member, the free end of said lever being connected to the end of said crank.

5 3. A gas stove comprising a tubular member having both ends closed, said member having openings near each end; an M-shaped bracket for supporting said tubular member; a funnel-shaped member secured to the tubular member at said openings; a valve reciprocably mounted in said opening, said valve member having a conical head; downwardly extending members projecting from said conical portion, said valve member having a central stem having a transverse opening near its ends; a lever pivotally connected to said bracket at one end and passing through the opening in the valve stem; an operating member pivotally connected to the bracket.

4. In a gas stove having a tubular member having its ends closed and provided with openings near each end; a funnel-shaped burner member having an opening in its narrow end, said funnel-shaped member being attached to the tubular member in such a manner that its opening registers with the opening in the tubular member; an M-shaped bracket for supporting said tubular member; a strap passing over the tubular member and secured at its ends to the supporting bracket, said tubular member and supporting bracket having registering openings diametrically opposite to the first mentioned opening; a valve member reciprocably mounted in the first mentioned opening, said valve member having a conical head with downwardly extending radially spaced guide members; a central stem secured to the valve member and projecting through the openings in the tubular member and supporting bracket, said stem having a transverse opening near its end; a lever extending through the opening in the stem, one end of said lever being hingedly connected to the bracket; an adjusting member rotatably supported by the bracket, said adjusting member having a crank arm, the free end of the lever being operatively connected to the end of the crank arm; and friction means for holding the adjusting member in position.

5. In a gas stove having a tubular member having its ends closed and provided with openings near each end; a funnel-shaped burner member having an opening in its narrow end, said funnel-shaped member being attached to the tubular member in such a manner that its opening registers with the opening in the tubular member; an M-shaped bracket for supporting said tubular member; a strap passing over the tubular member and secured at its ends to the supporting bracket, said tubular member and supporting bracket having registering openings diametrically opposite to the first men-

tioned openings; valve member reciprocably mounted in the first mentioned opening, said valve member having a conical head with downwardly extending radially spaced guide members; a central stem secured to the valve member and projecting through the openings in the tubular member and supporting bracket, said stem having a transverse opening near its end; a lever extending through the opening in the stem, one end of said lever being hingedly connected to the bracket; an adjusting member rotatably supported by the bracket, said adjusting member having a crank arm, the free end of the lever being operatively connected to the end of the crank arm; and friction means for holding the adjusting member in position, said friction means comprising a spring.

6. In a gas stove having a tubular member having its ends closed and provided with openings near each end; a funnel-shaped burner member having an opening in its narrow end, said funnel-shaped member being attached to the tubular member in such a manner that its opening registers with the opening in the tubular member; an M-shaped bracket for supporting said tubular member; a strap passing over the tubular member and secured at its ends to the supporting bracket, said tubular member and supporting bracket having registering openings diametrically opposite to the first mentioned opening; a valve member reciprocably mounted in the first mentioned opening, said valve member having a conical head with downwardly extending radially spaced guide members; a central stem secured to the valve member and projecting through the openings in the tubular member and supporting bracket, said stem having a transverse opening near its end; a lever extending through the opening in the stem, one end of said lever being hingedly connected to the bracket; an adjusting member rotatably supported by the bracket, said adjusting member having a crank arm, the free end of the lever being operatively connected to the end of the crank arm; friction means for holding the adjusting member in position; friction means comprising a spring for holding said adjusting member in position; and means telescopically connected to the adjusting member for turning the same.

7. A gas stove comprising a tubular member having both ends closed, said member having openings near each end, an M-shaped bracket for supporting said tubular member, a funnel-shaped member secured to the tubular member at said openings, a valve reciprocably mounted in said opening, said valve member having a conical head, a valve stem attached to said valve substantially in line with the axis of the conical head, said stem having a transverse opening near its

end, a lever pivotally connected to said bracket at one end and passing through the opening in the valve stem, and an operating member pivotally connected to the bracket.

8. In a gas stove having a tubular member having its ends closed and provided with openings near each end, a funnel-shaped burner member having an opening in its narrow end, said funnel-shaped member being attached to the tubular member in such a manner that its opening registers with the opening in the tubular member, an M-shaped bracket for supporting said tubular member, a strap passing over the tubular member and secured at its end to the supporting bracket, said tubular member and supporting bracket having registering openings diametrically opposite to the first-mentioned opening, a valve member reciprocally mounted in the first-mentioned opening,

said valve member having a conical head, a central stem secured to the valve member and projecting through the openings in the tubular member and supporting bracket, said stem having a transverse opening near its end, a lever extending through the opening in the stem, one end of said lever being hingedly connected to the bracket, an adjusting member rotatably supported by the bracket, said adjusting member having a crank arm, the free end of the lever being operatively connected to the end of the crank arm, and friction means for holding the adjusting member in position.

In testimony whereof we affix our signatures.
